[57] CLAIM

The ornamental design for a cultivator tine, substantially as shown.

DESCRIPTION

FIG. 1 is a side elevational view of a cultivator tine showing my new design;

FIG. 2 is a side elevational view thereof taken from the right in FIG. 1, the opposite side being a minor image of the side shown herein;

FIG. 3 is a perspective view thereof; and

FIG. 4 is a top plan view thereof.

FIG. 1

FIG. 2

FIG. 4

FIG. 3
